UNITED STATES PATENT OFFICE.

THEODOR KORTHÄUER, OF SIEMENSSTADT, NEAR BERLIN, GERMANY, ASSIGNOR TO AUTOMATIC ELECTRIC COMPANY, OF CHICAGO, ILLINOIS, A CORPORATION OF ILLINOIS.

TELEPHONE-EXCHANGE SYSTEM.

Application filed December 9, 1921. Serial No. 521,264.

To all whom it may concern:

Be it known that I, THEODOR KORTHÄUER, a German citizen, and resident of 9, Schulstrasse, Siemensstadt bei Berlin, Germany, 5 have invented certain new and useful Improvements in Telephone-Exchange Systems, of which the following is a specification.

The invention relates to telephone systems with differently operated exchanges, the object being to facilitate connection between subscribers belonging to exchanges operated in different ways. The invention consists in that trunk lines are directed by 10 switching operations on the part of the operator at the calling subscriber's exchange, whereby, at the same time an impulse transmitting device is connected up, and the control of the impulses for automatically setting a route selector of 15 the trunk line is controlled. In this way the necessity for any special attention to the impulse device on the part of the operator is obviated. The switching 20 operations to be performed by the operator are reduced to a minimum, and consist, for instance, solely in plugging the trunk-line jack. The invention presents special 25 advantages for telephone systems in which it is impracticable to reach all the other exchanges from one exchange. In such cases 30 the route selector is located in an exchange from which all the others can be reached.

According to the invention, the switching 35 operations of the operator preferably set in action a special selecting switch which connects up the impulse sender to the trunk line, starts it and directs the transmission of the impulses. In telephone systems in 40 which the trunk lines are reached through jacks, it is advisable to allot to a trunk line several jacks at an operating position, and to direct the trunk line by plugging 45 one of these jacks.

According to the invention, in the case 50 of telephone installations on the single-plug system, the directing of a trunk line, after the same is taken into use, is effected by operating a key, there being only one set of keys for this purpose, to all the trunk lines of an operating position.

The trunk line jacks at an operating position are divided into groups correspond-

ing to the different exchanges, and the impulse sending device is provided with a 55 contact for each of these groups. The switching arrangement allotted to the jack groups, or the lines coming from the directing keys to the impulse device, are preferably connected up in inverse numerical order. A particularly advantageous embodiment consists in setting the impulse sending 60 device (after the position selector has been set on a jack) on the contact corresponding to the jack group taken into use by the position selector. The switching-in of the impulse sender for transmitting impulses during its continued movement to its initial position is effected after a route selector 65 has been connected up. 70

Two embodiments of the invention are diagrammatically illustrated in the drawings. Fig. 1 shows the grouping of the jacks and of the selecting switch for connecting up the impulse sender to a trunk line and the numerical impulse receiver adapted to be connected up to the trunk lines. Figs 2-5, inclusive, illustrate in detail the direction traversed, by the current 75 in the arrangement according to Fig. 1. Figs. 6-8, inclusive, represent a circuit arrangement for installations on the single-plug system. Figure 9 shows a modified arrangement for giving the operator a distinctive clearing signal. 80 85

The subscriber h_1 (Fig. 1) belonging to the manual exchange IV is provided at the A position with the usual calling signal and the answering jack AK_1 . The operator answers, in known manner, after inserting 90 the answering plug $Astp$. Different groups of trunk-line jacks are situated in the jack field of the position. Through the jack AK_1 , connection can be set up with exchange III by way of one of the jacks VK_2 . If the calling subscriber desires, for example, to be put through to exchange III the plug $Vstp$ is inserted in one of the jacks VK_2 , for example jack 500. This sets the position selector PW automatically on this jack and starts the first pre-selector $I.VW 501$ which takes into use a free second pre-selector, for example $II.VW 502$, and this switch finds a free route selector, for example the first selector $I.GW 503$. As already explained, the position selector PW is set on the jack 500. 95 100 105

Accordingly, its wiper 504 finds itself in group 1—in fact on contact 505. By this means, the impulse sender, consisting of an impulse selector JW, is caused to set itself 5 on the contact 506. At the impulse selector JW, the lines coming from the position selector PW are connected in inverse order to the numerical arrangement of the jacks. Consequently, assuming the route selectors 10 to be provided with ten groups of lines each, the group 1 will be situated on the tenth contact of the impulse selector. After the first selector I.GW 503 has been connected up the set impulse selector JW is 15 caused to continue running until it reaches its position of rest, thus sending impulses through the trunk lines to set the route selector I.GW 503. Since the impulse selector JW is set on the tenth contact, the position 20 of rest is reached in one step and only one current impulse is sent out and the route selector is accordingly moved on to the first contact group, the lines of which lead to the exchange III. In this contact group the 25 route selector I.GW 503 automatically hunts for a free line, the operator at exchange III then completing the connection in known manner. After the setting of the route selector I.GW 503, the position selector PW and the impulse selector JW are released, 30 and can be used for another connection.

In detail, the operating of an installation of this kind according to Figs. 1-5, inclusive, proceeds as follows:

35 The exchange IV (Figs. 1 and 2) serves, in addition to manual subscribers—for example h_4 —for automatic subscribers, for example s_4 , who are enabled by switching operations performed by the operator to connect themselves up with subscribers of an automatic exchange (for example VI) or with a group of automatic subscribers of the manual exchange IV.

Assuming, in the first place, that the manual subscriber h_4 , desires to be put through to 45 the subscriber h_3 of the manual exchange III, when the receiver at the sub-station h_4 (Fig. 2) is removed, the calling relay A_r_1 operates by current passing through the subscriber's lines a , b , and connects up the calling lamp AL_1 at the working contact 1; the lamp AL_1 lights over the circuit battery, call lamp AL_1 , contacts 2, 1 and earth. The operator at position A of exchange IV inserts 50 the plug AStp into the corresponding answering jack AK_1 , thereby energizing the cut-off relay TR_1 , which opens the contact 2, so that the call lamp AL_1 goes out. The supervisory signal lamp SL_1 does not light 55 up, the resistance of winding I of the relay TR_1 being too high.

After answering, the operator inserts the connecting plug VStp in the trunk-line jack VK_2 , thus closing the contact 3, and connecting up the starting relay An as follows:

earth, contact 3, upper winding of relay R_3 , contact 4 resistances 5 and 6 relay An to battery. The relay An completes at its contact 7 the circuit for the motor magnet D_3 of the position selector PW. When the wipers of the position selector PW driven by the magnet D_3 encounter the trunk line of the plugged jack VK_2 the testing relay P is energized in the following circuit; battery working contact 8, windings I and II of the testing relay P, wiper 9, contact 10, resistance 5, contact 4 upper winding of relay R_3 , and contact 3 to earth. The relay P operates, 70 breaking the circuit of the rotary magnet D_3 at the contact 11, and short circuiting its high-resistance winding I at the contact 12. 75

The rotary magnet D_5 of the first pre-selector I.VW' is connected up, through the contact 13 of relay P as follows: Earth, contact 13, wiper 14, bank contacts 15, relay 80 contact 16, rotary magnet D_5 , and its interrupter to battery.

When the first pre-selector I.VW' has found a free second pre-selector II.VW', the testing relay T_3 is energized as follows; 85 earth, working contact 17, of relay P, Fig. 5, wiper 18 bank contact 19, windings I and II of the relay T_3 , lower winding of relay R_3 , c lead and test wiper of the first pre-selector I.VW', winding I of relay R_2 , contact 90 20, winding II of relay R_2 to battery. By opening, its contact 16, relay T_3 breaks the circuit of the motor magnet D_5 , and short circuits the winding I of relay T_3 at the contact 21, thus guarding the engaged 95 second pre-selector II.VW' from being taken into use by any other first pre-selector I.VW'. At the second pre-selector II.VW' the relay R_2 completes the circuit 100 for the motor magnet D_6 at its contact 22, and prepares at contact 23, the circuit for the testing relay T_5 . When a free route selector I.GW has been found, the testing relay T_5 is energized in the following circuit: 105 earth at contact 13 of relay P, Fig. 5, wiper 14, bank contact 15, relay contact 21, winding II of relay T_5 , lower winding of relay R_3 , c conductor and test wiper of pre-selector I.VW', winding I of relay R_2 , contact 110 23, windings I and II of relay T_5 , test wiper of pre-selector II.VW', c conductor of selector I.GW, contacts 24, 25, winding I of relay V_3 , winding of relay C_1 to battery. The relay T_5 breaks the circuit for the rotary 115 magnet D_6 at the contact 26, disconnects the winding II of relay R_2 at the contact 20, short-circuits the winding I of relay T_5 at contact 27, and switches the speaking leads a and b through at the contacts 28 and 29. 120

The setting of the position selector PW on the plugged trunk-line jack VK_2 completes the circuit for the motor magnet D_4 of the impulse selector JW as follows: earth, contact 30 of relay P, rotary magnet D_4 , contact 31, interrupter to battery. When the 125 130

impulse selector JW finds the jack group taken into use by the position selector PW, the testing relay P_1 is energized in the following circuit, battery, windings I and II of relay P_1 , wiper 32, bank contacts 33, 34 wiper 35 of position selector PW, contact 36 to earth. The relay P_1 operates, short-circuits its winding II at its contact 39 and locks itself energized over contacts 36 and 10 37, wiper 38 and contact 39.

In the first selector I.GW the relays V_3 and C_1 are energized. Moreover, the relay Y, Fig. 2 is connected up in the impulse selector JW, circuit as follows: earth I.GW 15 selector shaft back contact 40, contact 41, b-lead, contact 29, b-line wiper, contact 411, winding I of relay T_4 , bank contact 42, wiper 43, contact 44, relay Y and contact 45 to battery. In this circuit the relay Y alone 20 operates and not the relay T_4 , the resistance of relay Y being too high. The relay Y opens the contact 44 and thereby inserts the resistance 46 in its own circuit. Moreover at the contact 47, the relay J is energized 25 through the contact strip 48 and wiper 49. The relay J completes the circuit for the rotary magnet D_4 through the contacts 50 and 51 and at contact 511 sends out an impulse to the first selector I.GW as follows:— 30 earth, contact 511, wiper 52, bank contact 53, contact 54 of relay T_4 a-lead, contacts 28, 400, winding I of relay A_1 to battery. The relay A_1 completes the circuit for the lifting magnet H at the contact 52 as follows: battery, 35 lower winding of relay V_3 , lifting magnet H, contacts 52 of relay A_1 , 53 of relay V_3 , 54 of relay C_1 to earth. By this means the relay V_3 is kept energized during a series of impulses, even after the opening of the 40 contact 25. Through the contact 55, which is closed at the first lifting movement, the winding II of relay C_1 is connected up.

The motor magnet D_4 of the impulse selector JW short-circuits the impulse relay 45 J at the contact 56, thus making this relay release; and consequently the circuit for the rotary magnet D_4 is broken at contact 50, and that for relay A_1 at contact 511. In case the wipers of the switch JW do not 50 reach a position of rest upon the above operation of the associated motor magnet, the relay J operates again in the above described energizing circuit, and sends another impulse to the first selector I.GW. This 55 cycle repeats itself until the impulse selector JW has reached its position of rest.

In the present case, however, the position of rest is reached upon the first operation of the motor magnet D_4 after it is restarted, 60 whereupon the relay J is disconnected and the relay Y is short circuited over the wiper 49 and contact 57. The relay T_4 is now energized through contact 45 of relay P_1 wiper 49, contacts 57, 44, wiper 43, bank contact 65 42. Relay T_4 disconnects the position selector

PW by opening the contact 4; and connects up its winding II by closing the contact 58, and, by closing the contact 59, switching through the test conductor c from the trunk line jack VK_2 to the first selector I.GW. 70

In the first selector I.GW the relay V_3 becomes released when the impulse comes to an end, and connects up the rotary magnet D_6 as follows: battery, rotary magnet D_6 , contacts 60 of relay A, 61 of relay V_3 , 62 of relay P_2 , 63 of relay C_1 , interrupter to earth. When the first selector I.GW finds a free line, the following circuit is set up; earth, winding I of relay P_2 , winding II of relay A_1 , contact 64, test wiper of the first selector I.GW, windings I and II of relay TR_3 to battery. The relays P_2 and TR_3 operate, but, owing to the high-resistance winding I of relay TR_3 , the relay A_1 cannot operate. The relay P_2 breaks the circuit of the rotary magnet D_6 at the contact 62, and short circuits its own winding I through the contacts 65 of relay C_1 and 66 of relay P_2 . The holding winding II of relay P_2 is connected up at its contact 67. In addition its contact 41 is opened, and its contacts 68 and 69 are closed, thus switching the speaking leads a, b, through to the line that has been found disengaged. 80

At the contact 691, the relay TR_3 of the seized trunk line completes the following circuit; battery, contact 691, relay LR_2 , b-lead of the cord circuit at position B, relay HSR to earth. The relay HSR at its contact 70 connects up the relay SR_1 , and the relay SR_1 connects up the clearing signal lamp BSL , (acting in this case as call lamp at the B position) through the contact 73 of the auxiliary relay HR , by opening the contact 71 and closing the contact 72. The operator at B enquires, by throwing over the speaking key 74 in known manner, and tests the multiple jack VK_1 of the desired subscriber h_3 . If the line is free, the operator inserts the plug $VStp_1$, thus completing the circuit; battery, relay B , winding I of relay SR_2 , sleeve 75 of plug $VStp_1$, sleeve 76 of jack VK_1 , winding I of relay TR_4 to earth. The relay B operates and completes at its contact 77 the circuit for the relay H_r , and at contact 79 a circuit for the winding II of relay SR_2 . The current through the low-resistance winding II of relay TR_4 causes the relay SR_2 to operate, and, by opening its contact 80, prevents the relay AB from operating. 100

The relay H_r opens its contact 73 and thus puts out the call lamp BSL , at position B. A further circuit for this lamp is prepared by closing the contact 78. In addition, the relay H_r completes, at its contact 83, the circuit for the calling relay P_r , which is energized intermittently through an interruptor, and sends ringing current over the subscriber's line at its contact 84 and 85. 110 120 125 130

At the contact 185 of relay P_r the following circuit is completed: battery, contacts 185 of relay P_r , 86 of relay H_r , 87 of relay SR_1 , impedance coil D_r , a -lead and relay LR_1 to earth. The relay LR_1 at its contact 88 short-circuits the winding I of relay TR_3 , thus increasing current through the lead c_1 so that the relay A_1 in the first selector $I.GW$ operates. Relay A_1 closes its contact 141, 10 and by short-circuiting the high-resistance winding II of relay C_1 causes the relay R_3 of the first preselector $I.VW'$ to operate. The relay R_3 closes its contact 189, and short circuits the resistance 92, thereby increasing the current through the jack sleeve 90 and the sleeve 91 of the calling plug $VStp$, 15 so that the clearing-signal lamp SL_2 flashes in unison with the intermittent operation of relay PR . The flashing of the lamp SL_2 indicates to the operator at A that ringing current is being sent over the wanted subscriber's line.

If the wanted subscriber h_3 answers, the relay Ar_4 operates and opens its contact 82, 20 thus disconnecting the winding II of relay TR_4 and reducing the current through the winding I of relay SR_2 so that the effect of this winding is rendered equal to that of its differentially connected winding II. 25 Thereby causing its armature to fall back connecting up at contact 80 the circuit previously prepared, at contact 93 of relay Hr_1 , for the relay AB which connects itself up, at contact 94 and contact 95 of relay SR_1 to 30 a holding circuit dependent on SR_1 . The relay AB at its contact 96, breaks the circuit for the ringing relay PR , and at its contacts 97 and 98 switches the speaking leads into the B cord circuit.

40 When the calling subscriber hangs up his receiver at the end of the conversation, the relay AR_4 releases and at its contact 99, connects up the low-resistance winding II of relay TR_4 parallel with its high-resistance winding I. By this means the current through the sleeve of jack 100 and contact 101 of the answering plug $AStp$ is increased so that the clearing signal lamp SL_1 lights up. When the called subscriber hangs up 45 his receiver, the relay AR_4 releases and closes its contact 82 and connects up the winding II of relay TR_4 in parallel with its winding I so that the relay SR_2 operates. This relay completes, at its contact 81, the 50 circuit prepared for the relay LR_1 at 81'. The winding I of relay TR_3 is short-circuited at the contact 88, and the current in the lead c_1 is thereby increased so that the relay A_1 is now energized. This relay closes 55 its contact 141 and thus brings into operation the relay R_3 of the preselector $I.VW'$ which closes the contact 189. The clearing-signal lamp SL_2 lighting up in consequence.

The operator at A takes the plug $VStp$ out 60 of the trunk-line jack VK_2 , thus depriving

the energizing circuit of the relays T_3 , T_4 , T_5 and C_1 of current. The relay C_1 opens at its contact 65 the circuit for the relay P_r and closes, through the contacts 102 and 103, the circuit for the release magnet M of the 70 first selector $I.GW$, the latter being released. By opening the contact 64, the relay TR_3 is released, opening the contact 69 and thus causing the relay HSR to fall back. The relay HSR disconnects, at the contact 75 70, the relay SR_1 , which completes, at the contact 71 the circuit prepared for clearing the signal lamp BSL at the contact 78.

The B operator takes the plug $SVtp$ out of the jack VK_1 of the called subscriber, 80 whereupon all the switching devices used are again in their normal position.

If an automatic subscriber s_4 of the manual exchange IV wishes to get through to a subscriber of the automatic exchange VI, he 85 calls up the manual exchange IV in the usual manner, by taking down his receiver. After the call lamp AL_2 has lit up, the operator inserts the answering plug $AStp$ into the jack AK_2 and answers in known manner, and then inserts the connecting plug $VStp$ in the auxiliary jack HK_2 allotted to the line of the automatic subscriber S_4 . By the closing of the jack contact 111, the rotary magnet D of the first pre-selector 90 $I.VW$ allotted to the subscriber's line is connected up as follows: earth, contact 111, conductor 112, armature 113 and its working contact of the line relay AR_2 , contact 144, rotary magnet D to interrupter and battery. 100 When the first pre-selector $I.VW$ finds a free second pre-selector $II.VW$ the energizing of the cut-off relay T_1 switches the speaking line over from the answering jack AK_2 to the line wipers of the pre-selector 105 at the contacts 115 to 118, inclusive. The first rotary movement of the first pre-selector $I.VW$ opens the contact 119 through which as will be described later—the two clearing signal lamps SL_1 and SL_2 of the 110 cord circuit are connected up at the end of the conversation. The second pre-selector $II.VW$ is connected up in the known manner. From the second pre-selector $II.VW$ as can be seen from the drawing the same 115 trunk lines can be taken into use as can be reached by the operator at A through the trunk-line jack VK_2 and the pre-selectors $I.VW'$ and $II.VW'$. When a trunk line is taken into use by an automatic subscriber, 120 however, a repeater Ue is connected up, but not when the trunk line is taken into use by the operator. Taking the repeater Ue into use connects up therein, through the lead e , the contact 131, and the resistance 132, the relay C_3 which closes its contact 133 and thereby switches the e -lead through to the first selector $I.GW$. In trunk lines taken into use by the operator, the contact 131 of the relay C_1 is opened, so that the test wiper 130

of the second pre-selector II.VW does not find any potential on these engaged lines. At the repeater Ue, the bridge relay A operates after the speaking leads have been 5 switched through, and connects up the release relay V₁ at the contact 120. This relay switches the c-lead through at the contact 134, the relay C₃ being short-circuited.

When the subscriber *s₄* sends out the 10 pulses for setting the first selector I.GW the relay A₁ is controlled through the contacts 121 and 122. The setting of the first selector I.GW then proceeds in the known manner.

15 When the subscriber hangs up his receiver at the end of the conversation, the set selecting devices are released by the opening of the contacts 123, 124 and 134 at the repeater Ue. The opening of the contact 134 20 deprives the relays C₁, T₂ and T₁ of I.GW, II.VW, and I.VW, respectively, of current. The relay C₁ releases the set numerical current impulse receiver in the manner already described, by closing the contact 102 and 25 opening the contacts 64 and 65.

By depriving the relays T₂ and T₁ of current, both the pre-selectors II.VW and I.VW are released. The first pre-selector I.VW returns to its normal position and 30 thereby connects up the two clearing signal lamps SL₁ and SL₂ as follows: earth, contacts 119, 123 on the one hand through the winding II of relay TR₂, jack sleeve 126, plug contact 101, clearing-signal lamp SL₁ 35 to battery, and on the other hand through resistance 127, jack sleeve 128, plug contact 91, lamp SL₂ to battery. Hereupon the operator takes both plugs ASTp and VStp out of the jacks AK₂ and HK₂.

40 In the embodiment of the invention according to Fig. 3 the A position is provided with only one answering plug ASTp, to which is connected a line leading to a first pre-selector I.VW. The call of the subscriber *h₄* proceeds in the following manner: Plugging the answering jack with the plug ASTP operates the relay R, which causes the position selector PW to move on to the 45 answering plug that has been taken into use.

50 If, for instance, the subscriber *h₄* wishes to be put through to a subscriber of the manual exchange III, the operator presses the key Ta₁. This switching operation on the part of the operator must be regarded as

55 equivalent to plugging a trunk line. Pressing this key directs the trunk line that is taken into use, since it determines the number of current impulses to be sent out. The setting of the position selector PW proceeds in the manner described with reference to Figs. 2 and 2^a and needs no further explanation. The same also applies to the setting of the first and second pre-selectors I.VW and II.VW. Since the operator does 60 not direct the trunk line until after taking

into use and answering, an appreciable amount of time elapses after the plugging in and the starting of the preselectors and before the starting of the sending switch JW responsive to the operation of the key 70 Ta₁, during which a route selector is connected up before transmission of impulses can take place. Consequently, no special devices are needed for delaying the connecting up of the impulse device until after a route 75 selector has been connected up.

Pressing the key Ta₁ connects up the rotary magnet D₁ of the impulse selector as follows: earth, contacts 141 and 142, rotary magnet D₁, contact 143 and interrupter to 80 battery. When the impulse selector finds the depressed key Ta₁, the relay P₁ is energized as follows: earth, key contact 144, bank contact 145, wiper 146, relay P₁ to battery. The relay P₁ closes the contact 147, 85 and thereby maintains itself energized independently of the key Ta₃, by way of the wiper 148 and earth to contact 149. P₁ also opens the contact 143 and closes 151 the impulse relay J being thereby energized as 90 follows: battery, contact 151, wiper 152, contact 153, relay J, contacts 142 and 141 to earth. At the contact 250, the relay J sends out an impulse to the selector (I.GW) over the wiper 251, and this relay also connects 95 up the rotary magnet D₁ through the contact 153. The impulse selector moves one step. The rotary magnet D₁ short-circuits the relay J at the contact 154 and thus releases the said relay. If it were not for the fact that the impulse selector has reached its normal position by this one step, the impulse relay J would operate again, at once, in the above mentioned circuit and the cycle 100 of operations would be repeated until the impulse selector has attained its normal position. At any rate, when the normal position of the impulse selector is reached, the relay T₂ is energized via battery, contact 151, wipers 152 and 156, bank contact 157, 105 winding I of relay T₂, bank contact 158, wiper 159, contacts 160, 142 and 141 to earth. The relay T₂ opens the contact 161 and closes 162. This short-circuits the relay R and connects up the winding II of the 110 relay T₂. The relay R allows its armature to drop, and releases the position selector, the keys and the impulse selector, so that these 115 can be used for a new connection.

The setting of the numerical impulse receiver I.GW is effected in the known manner. The clearing signal is given, in this embodiment, through a special lead *z*. When the called subscriber hangs up his receiver, relay A₁ on the first selector I.GW 120 operates by increased current over the associated third conductor as hereinbefore described, and by closing the contact 163, connects up the clearing signal lamp SL₂. The connection is cut off by taking the an- 125 130

swering plug ASTP out of the answering jack AK_2 , whereupon the selecting devices are released by the relay T_2 releasing and opening the contact 164.

6. The automatic subscriber s_4 of the manual exchange operated on the single-plug system, is allotted a key HT. When the subscriber s_4 calls up the exchange in the known manner and wishes to be put through to 10 an automatic subscriber or to one of a group of automatic subscribers of the manual exchange, the operator, after answering, presses the key HT. This keeps the cut-off relay TR_2 energized through the contact 171, and the resistance 172. The rotary magnet of the first pre-selector I.VW is connected up through the contact 173. The setting of the pre-selecting devices and the taking into use and setting of the numerical 15 impulse receiver, which can also be reached by the operator, are effected in the known manner.

After the release of the selecting devices responsive to the calling subscriber replacing his receiver, the call lamp AL_2 is connected up, to act as clearing signal, as follows: earth, contact 174, resistance 175, contact 176, lamp AL_2 to battery. Owing to the resistance 175, the call lamp AL_2 gives 20 a dull light and thus gives the operator a clearing signal that differs definitely from the calling signal. In comparison with the first embodiment according to Fig. 1 this circuit arrangement presents the advantage 25 that there is no need to use a cord circuit during a connection between two automatic subscribers. As soon as the key HT has been pressed, the answering plug ASTP can be taken out of the jack AK_2 .

30 Figure 3^a shows how an interrupter 176 can be connected in the circuit of lamp AL_2 in order to give the operator a flash-clearing signal. This is desirable in some cases where the signal given by the dim 35 illumination of the call lamp is not sufficiently conspicuous to attract the operator's attention.

What I claim and desire to protect by Letters Patent is:—

50 1. In a telephone system, two exchanges, means including an operator's link circuit and directly controlled automatic switching means whereby an operator can set up a connection from a calling subscriber's line in one exchange to a line in the other exchange, and means whereby said operator can place the setting up of the connection under the control of the said calling line, said control being exercised over a path exclusive of said link circuit.

55 2. In a telephone system, two exchanges, means including an operator's link circuit and directly controlled automatic switching means whereby an operator can extend a connection from a calling subscriber's line

in the first exchange to a line in the second exchange, and means whereby the operator can assign the directive control of the automatic switching means to the said calling line, said control being exercised over a 70 path exclusive of said link circuit.

3. In a telephone system, a calling line, an automatic switch individual to said line, a line relay for said switch normally connected to said line but having no control over said switch, and means controlled by an operator for placing said automatic switch under the control of said line relay.

4. In a telephone system, a calling line, 80 an individual line relay normally connected to said line, automatic switching means over which said line relay has no control, and means individual to said line controlled by an operator for placing said automatic switching means under the control of said line relay.

5. In a telephone system, a line terminating at an operator's position, means including an operator's cord circuit for answering a call on said line and for extending a connection from said line to a called line, automatic switching means over which said calling line has no control, a spring jack at said operator's position individual to said calling line and means whereby the operator can place said automatic switching means under the control of said calling line by inserting a plug of her cord circuit into said spring jack.

6. In a telephone system, an operator's position, a plurality of trunks terminating thereat, means for taking any one of said trunks for use, an impulse emitting device common to said trunks, means for connecting said device with any one of said trunks when the latter is taken for use, and means for transmitting a series of impulses from said device to the last mentioned trunk after the same is connected with said device, the number of impulses in the series being dependent upon the trunk taken for use.

7. In a telephone system, an operator's position, a plurality of trunks terminating thereat, a plurality of automatic directly controlled switches, means for taking any one of said trunks for use, means responsive thereto for associating the trunk taken for use with one of said switches, an impulse emitting device, means for associating said device with any one of said trunks when the latter is taken for use, means for transmitting a series of impulses from said device to the last mentioned switch, the number of impulses in the series dependent upon the trunk taken for use.

8. In a telephone system, a trunk line, a plurality of incoming lines at the originating end of said trunk line, a corresponding plurality of outgoing lines at the distant end, an impulse sending device at the orig-

- inating end common to all of said incoming lines, automatic switching mechanism responsive to the seizure of any incoming line for connecting said device to such line, 5 and selecting mechanism at the distant end of said trunk subsequently controlled by said device for connecting the trunk with the outgoing line corresponding to the incoming line in use.
- 10 9. In a telephone system, a trunk line, a plurality of incoming lines at the originating end of said trunk line, a corresponding plurality of outgoing lines at the distant end, automatic switching mechanism 15 responsive to the seizure of any incoming line for connecting such line to said trunk, an impulse sending device, automatic switching mechanism for connecting said device to the incoming line in use, a selector at the distant end of said trunk, and means 20 for automatically operating said device subsequent to the connection thereof with the incoming line for transmitting a series of impulses over the trunk to operate said 25 selector to connect said trunk with the outgoing line which corresponds to the incoming line in use.
10. In a telephone system, a trunk line, a plurality of incoming lines at the originating end of said trunk line, a corresponding plurality of outgoing lines at the distant end, automatic switching mechanism responsive to the seizure of any incoming line for connecting such line to said trunk, an impulse sending device, automatic switching mechanism for connecting said device to the incoming line in use, a selector at the distant end of said trunk, and means responsive to the connection of the incoming line to the trunk or the connection of the device to the incoming line, whichever is last established, for operating said device to transmit a series of impulses over the trunk to operate said selector to connect said trunk with the outgoing line 40 which corresponds to the incoming line in use. 45
